UNITED STATES PATENT OFFICE.

HEINRICH KOPPERS, OF ESSEN-RUHR, GERMANY, ASSIGNOR TO THE KOPPERS DEVELOPMENT CORPORATION, OF PITTSBURGH, PENNSYLVANIA, A CORPORATION OF PENNSYLVANIA.

GAS RETORT.

Application filed July 8, 1921, Serial No. 483,143, and in Germany February 2, 1920.

This invention relates to retort ovens, such as gas retorts, and is especially applicable to such retort ovens as are provided with inclined retorts assembled in a joint envelope 5 or chamber and combined with preheating of the fuel gas and air in regenerators which operate on the reversal principle.

It has been provided to construct a retort oven constituted of several retorts assembled 10 in a joint envelope and providing for pre-heating of gas and air in single-chamber regenerators, combined with an arrangement for the distribution of the two fuels, by means of which uniformity in heating of the retorts is promoted. Such a basic distribution 15 is of special importance for inclined retort ovens because, as is well known, the different heights occasion irregularities due to the tendency of the buoyant hot gases to flow 20 toward the upper portion of the inclined space, which tend to impair the regularity of the flame flow and distribution. In the shell enclosing the retort group it is, of course, impossible to prescribe for the flame compulsory routes as exact or accurate as is the case 25 in the heating walls of chamber ovens (coke ovens) brought now-a-days to a high degree of perfection from a heating point of view.

In addition to this lack of uniformity in 30 regard to the flow tendencies of the buoyant hot gases, there also appears a correlated phenomenon in that, notwithstanding the correct relationship of the gas and air supply generally, some burners receive more gas 35 and others more air. It often happens that combustion takes place beyond the oven proper because of delayed mixing of the oxygen, producing an uneconomic after-burning, inasmuch as the oven proper is no longer 40 benefited thereby.

According to the invention, these two phenomena are to be eliminated together, that is to say, in slanting retorts both the one-sided effect of the flow tendencies of the buoyant hot gases is to be compensated and a systematic joint guidance of the flames of the different burner places is to be made compulsory within the oven proper. This is accomplished by erecting, at the turning place 45 of the flame path above the retorts, that is to say in a nine-retort oven above the central row of retorts, a wall extending up to under the arch of the shell and having only at

one place a passage for the gases which must go through at that point. This port in the central separating wall, therefore, must be compared in the first place with the upper horizontal channel in coke ovens in which the gases of the different burner places are led together and then brought to the point of complete combustion. By locating this passage opening towards the lower end of the retorts, it is made possible to counteract the greater upflow tendencies of the buoyant hot gases on the other side, in so far as now the flame has to pass downward again.

In addition to the general objects recited above, the invention has for further objects such other improvements and advantages in construction and operation as are found to obtain in the structures and devices herein-after described or claimed.

In the accompanying drawings, forming a part of this specification and showing, for purposes of exemplification, a preferred form and manner in which the invention may be embodied and practiced, but without limiting the claimed invention specifically to such illustrative instance or instances:

Fig. 1 is a section taken crosswise of the retorts of a retort oven; and

Fig. 2 is a section taken longitudinally of the retorts.

The oven shown in the drawings is constructed and operated according to my co-pending application Serial No. 497,363, filed August 31, 1921, for gas retort, (which has now matured into Patent No. 1,663,847), for which I have filed an application in Germany Feb. 2, 1920, application No. K71945V/24c, and is provided above the central retort row with a separating wall 30 which separates the up-flow from the down-flow flues and extends 85 to the arch 10, whereby the envelope enclosing the retorts is divided into two compartments. In this separating wall or partition 30 an opening 31 is provided and given such dimensions in the first place that all the gases 90 must pass through here, intimately mixed, so that an after-burning of possibly still unburnt parts which might benefit the oven is brought about. Now, by arranging this opening 31 further at the lower end of the retorts, a counter-effect is obtained against the one-sided up-flow tendencies of the buoyant hot 100 gases in consequence of the oblique or in-

clined position of the retorts, so that an additional equalization is accomplished in regard to the heating.

The invention as hereinabove set forth is embodied in a particular form of construction, but may be variously embodied within the scope of the claims hereinafter made.

I claim:

1. In a gas retort structure, in combination :
 10 a plurality of retorts grouped in a flame chamber common to and enveloping said grouped retorts, said chamber being partitioned into two groups of flame flues, for alternate inflow and outflow, that surround said retorts and
 15 port into a crown-space in the top of said chamber above and extending over the group of said flues and retorts; a partition dividing said crown-space between the two portions thereof into which respectively the said inflow and outflow flues port, the said partition having in it a port that determines the place of the flow from the said inflow portion to the said outflow portion of said crown-space; and
 20 regenerators respectively connected with said alternately inflow and outflow flues; substantially as specified.

2. In a gas retort structure, in combination :
 a plurality of retorts grouped in a flame chamber common to and enveloping said grouped
 30 retorts, said chamber being partitioned into two groups of flame flues, for alternate inflow and outflow, that surround said retorts and port into a crown-space in the top of said chamber above and extending over the group
 35 of said flues and retorts; and a partition dividing said crown-space between the two portions thereof into which respectively the said inflow and outflow flues port, the said partition having in it a port that determines the
 40 place of the flow from the said inflow portion to the said outflow portion of said crown space; substantially as specified.

3. In a gas retort structure, in combination :
 a plurality of retorts grouped in a flame chamber common to and enveloping said grouped
 45 retorts, said chamber being partitioned into two groups of flame flues, for alternate inflow and outflow, that surround said retorts and port into a crown-space in the top of said
 50 chamber above and extending over the group of said flues and retorts; and a partition

dividing said crown-space between the two portions thereof into which respectively the said inflow and outflow flues port, the said partition having in it a port that is located 55 at one end of said crown-space and that determines the place of the flow from the said inflow portion to the said outflow portion of said crown space; substantially as specified.

4. In a gas retort structure, in combination :
 a plurality of inclined retorts grouped in a flame chamber common to and enveloping said grouped retorts, said chamber being partitioned into two groups of flame flues, for alternate inflow and outflow, that surround said 65 retorts and port into an inclined crown-space in the top of said chamber above and extending over the group of said flues and retorts; and a partition dividing said crown-space between the two portions thereof into which respectively the said inflow and outflow flues port, the said partition having in it a port that is located at the lower end of said crown-space 70 and that determines the place of the flow from the said inflow portion to the said outflow portion of said crown space; substantially as specified.

5. A gas retort structure principally for the production of gas and having in combination :
 several inclined retorts grouped in a flame 80 chamber common to and enveloping said retorts and having in it a plurality of individual burner places and connected with regenerators for preheating the gas and air with which said chamber is fired; and a partition dividing 85 into halves the said flame chamber enveloping said retorts, the said halves operating alternately, on draft reversal, for inflow and outflow, and the said partition having in it a port located near the lower end of the group 90 of inclined retorts and determining the place of flow from the inflow portion to the outflow portion of said partitioned chamber; whereby all of the off-gas from the individual burner 95 places in said flame chamber is directed in a common course to effect compensation of gas and air surplus and also counteract the unequal distribution due to the tendency of the hot gas to flow toward the upper end of the inclined retorts.

HEINRICH KOPPERS.
